[57] CLAIM

The ornamental design for a bowl with cover, as shown and described.

DESCRIPTION

FIG. 1 is a front elevational view of a bowl with cover, showing my new design, the left side, right side, and rear elevational views being identical thereto; FIG. 2 is a top plan view thereof; and, FIG. 3 is a sectional view thereof, taken along line III—III of FIG. 2.

The bottom plan view is plain and unornamented.

Fig. 1.
